UNITED STATES PATENT OFFICE.

FRANK G. HOTKA, OF CUDAHY, WISCONSIN.

GLOVE-SEWING MACHINE.

1,348,176.

Specification of Letters Patent.

Patented Aug. 3, 1920.

Application filed February 17, 1919. Serial No. 277,506.

To all whom it may concern:

Be it known that I, FRANK G. HOTKA, a citizen of the United States and resident of Cudahy, in the county of Milwaukee and 5 State of Wisconsin, have invented certain new and useful Improvements in Glove-Sewing Machines; and I do hereby declare that the following is a full, clear, and exact description thereof.

10 My invention relates to new and useful improvements in sewing machines for use in the manufacture of gloves and allied articles.

It is particularly desirable in work gloves 15 and other gloves wherein the wearer makes considerable use of the palm and inside surface of the fingers of his gloves, that said palm and inner surface of the glove fingers be as free as possible of seams. In providing a glove of this form manufacturers have adopted what is termed a "moccasin" type 20 of glove. In such a glove the finger seams are on the backs of the fingers so that the under surface of said fingers is smooth.

25 Heretofore gloves of this general character have been almost entirely made by hand as the ordinary type of leather sewing machine cannot perform the necessary functions. It is therefore the principal object 30 of the present invention to provide an attachment for a standard type of sewing machine which will permit gloves of this nature to be manufactured much more rapidly and at less cost than by the old hand methods.

35 With this general object in view the invention resides in certain novel features of construction, combination and arrangement of parts which will be hereinafter more particularly described and explained and shown 40 in the accompanying drawings which illustrate one embodiment of the invention, it being understood, however, that various changes may be made in the form and proportion of the several parts of the attachment without departing from the spirit of 45 the invention.

In these drawings:

Figure 1 represents a vertical sectional view of a standard sewing machine having 50 my invention applied thereto.

Fig. 2 is a horizontal section taken substantially on the plane of the line 2—2 of Fig. 1.

Fig. 3 is a vertical transverse sectional view on the plane of the line 3—3 of Fig. 1.

Fig. 3^a is a detail sectional view on the line 3^a—3^a of Fig. 3.

Fig. 4 is a view similar to Fig. 3 taken on the line 4—4 of Fig. 1.

Figs. 5, 6 and 7 are semi-diagrammatic 60 views showing the several steps in the operation of my improved machine on two pieces of leather or the like.

Fig. 8 is a fragmentary edge view of two pieces of material stitched together, the 65 stitching operation having been performed on a machine manufactured in accordance with my invention.

Fig. 9 is a plan view of a portion of the finger blanks from which a glove finger of 70 the "moccasin" type is to be made.

Fig. 10 is a plan view of one end of such a finger, the material being shown in Fig. 9.

Fig. 11 is a detail longitudinal sectional view of a "moccasin" type of glove finger. 75

Referring more particularly to the several figures of the drawing it will be noted that the standard form of sewing machine with which my invention is used consists essentially of a worktable 1 above which is supported by the standard 2 an overarm 3, said overarm carrying the usual head 4, the longitudinally extended main drive shaft 5, and the similarly positioned rock shaft 6. My improved mechanism is operated entirely 80 by these shafts 5 and 6 and is largely positioned beneath the overarm 3.

Since it is essential in the "moccasin" type of glove finger that the inner blank of leather, or other material, A be of greater 90 size than the outer blank B, it is necessary that the end or rounded portion of the first mentioned blank have its edge tucked or gathered so as to bring the said edge into position to be stitched to the corresponding edge of the other blank B. The invention illustrated is adapted to simultaneously form these tucks in the blank A and sew the two blanks A and B together. 95

Therefore in carrying out the invention 100 I position a tucking member or arm 7 which is substantially triangular in cross section, adjacent the awl 8 and needle 9.

The mechanism operated by the shafts 5 and 6 as heretofore set forth actuates this 105 tucker 7 to intermittently engage it with the lower blank A to produce a successive row of tucks, said tucker being located between the two blanks A and B as clearly indicated in Figs. 5, 6 and 7. The tucker 7 is carried by 110

a depending arm 10 which in turn is mounted on one end of an intermediately pivoted oscillatory rod 11. This rod 11 is slidably positioned in a pair of spaced bearings 12 of a yoke 13, the latter being pivoted to a support 14 mounted on the table 1.

The end of the rod 11 opposite to that which carries the tucker 7 is adapted to be operated upon by one arm 15 of a bell crank, 10 said bell crank being formed of this arm 15, a short rock shaft 16 journaled in the bearing of a bracket 17, and a rod 18.

The upper end of the rod 18 carries a roller 19 for operation in a cam groove 20 15 of a rotary cam 21, the same being keyed to the shaft 5. From Fig. 3 it will be seen that the cam groove 20 is of such shape that the rock shaft 16 will be oscillated to cause the raising and lowering of the arm 15 and the 20 consequent rocking of the rod 11 and the yoke 13 about the pivot of the latter. Thus a continuous rotary movement of the shaft 5 is changed to a substantially vertical reciprocal movement in the tucker 7 whereby to intermittently raise and lower the latter with respect to the work material being 25 operated upon.

A coil spring 22 is secured on the table 1 and has one arm 23 extended beneath the rod 30 11 to cause a quick upward movement of the adjacent end thereof with a resulting rapid downward movement of the tucker 7.

While the tucker is engaged with the work material it is desirable that the same be 35 moved approximately in a horizontal plane or relatively parallel to the surface of the work-table 1. This particular movement is procured by the oscillation of the rod 11 which is operated indirectly by the rotation 40 of the shaft 5. It might be here pointed out that the shaft 5 carries a second rotary cam 24 in the cam groove of which is disposed a roller mounted on the free end of the lever 25, the latter being connected intermediate 45 its ends with the rock shaft 6 by a connecting member 26.

Depending from the intermediate portion of the rock shaft 6 and fixed thereto so as to be oscillated thereby is a stem 27, the free 50 end of which is adjustably connected with a lever 28 intermediate the ends of the latter, and the lower end of this lever 28 is pivoted to a support 28' carried by the table 1. A rod 29 is adjustably fixed to the rod 11 adjacent 55 one of the bearings 12 of the yoke 13 and is connected by means of a link 30 and coupling members 31 to the lever 28. These coupling members 31 are slidably adjustable on the lever 28 and rod 29 respectively 60 whereby the amount of oscillation of the rod 11 may be varied, it being obvious that the oscillation of the rock shaft 6 is transmitted through the stem 27, and the other elements just enumerated, to said rod 11.

65 Referring to Fig. 3^a it will be noted that

the link 30 is also adjustable in length. In other words it is made in two sections, one of which carries a threaded stud 32 for engagement in the threaded socket 33 of the other. Thus by disconnecting the link 30⁷⁰ from the coupling member 31 by removing the screw 34, stud 32 may be screwed into or out of the socket 33.

With the mechanism thus far described the glove finger blanks will be properly associated at the same time and irrespective of the usual operations of the awl 8 and the needle 9. However, it is desirable at times to move the tucker away from the work material so as to render it inoperative. For 75 this purpose I have provided a cam member 35 pivoted to one of the bearings 12 of the yoke 13 and operable by a handle 36. When the handle is moved in one direction this cam member 35 engages the lower connecting portion of the rod 29 and moves it away from said bearing 12. This movement also causes the rod 11 to shift longitudinally and away from the work material. Upon movement of the handle 36 in the opposite direction the rod 11 is returned to its original position by the tension of an expansive spring 37. The hereinbefore described connection between the two parts of the link 30 is also adapted to permit the rod 90 29 to be shifted by the cam member 35 without deranging the other parts of the connection between the stem 27 and the rod 11.

From the foregoing description it will be seen that the tucker 7 is oscillated in two 100 directions, that is to say in planes at approximately right angles to each other. The vertical movement is obviously caused by the rocking of the rod 11, while the substantially horizontal movement is occasioned by 105 the partial rotation of said rod 11. Whenever the tucker is moved substantially horizontally it is engaged with the blank A of the glove finger and tends to move the same toward the awl 8 and the needle 9, thus causing the puckering or gathering of the edge of the material as is clearly shown in Figs. 5, 6, 7, and 10. When the limit of travel of the tucker in a horizontal direction is reached the same is raised upwardly and 115 rearwardly to return it to its original position, or to the position occupied before it is moved downwardly.

Since this machine does away entirely with hand labor it is believed that it will 120 be obvious that the cost of manufacture will be greatly lessened while the perfection of workmanship will be materially increased. Also in view of the fact that the mechanism may be used on types of machines now 125 generally employed in leather working establishments, the cost of gloves of this character will be further decreased.

I claim:

1. In a machine of the class described, 130

means for forming tucks in flexible material comprising a rock shaft, a tucking arm carried by the shaft, means for oscillating the rock shaft on its axis, and means for oscillating the rock shaft in the plane of its axis, said oscillations being simultaneous to swing the tucking arm in two directions at the same time.

2. In a machine of the class described, means for forming tucks in flexible material comprising an oscillatory arm, means for oscillating the arm vertically to intermittently engage the flexible material, and means for oscillating the arm substantially horizontally when the same is engaged with said material.

3. In a machine of the class described, a rod pivoted intermediate its ends, a tucking arm carried by the rod, means for rocking the rod to move the arm toward and away from the work material, and means for oscillating the rod when the arm is engaged with the work material, and means for varying the degree of oscillation to modify the size of the tucks.

4. The combination with a sewing ma-

chine, of a rod pivoted intermediate its ends, a tucking arm carried by the rod and disposed adjacent the needle of said machine, and means for rocking the rod to move the arm toward and away from the work material, and means for oscillating the rod when the arm is engaged with the work material to tend to move said material toward said needle.

5. The combination with a sewing machine, of a rod pivoted intermediate its ends, a tucking arm carried by the rod and disposed adjacent the needle of said machine, and means for rocking the rod to move the arm toward and away from the work material, and means for oscillating the rod when the arm is engaged with the work material to tend to move said material toward said needle and means for moving the arm away from the needle to render the former inoperative.

In testimony that I claim the foregoing I have hereunto set my hand at Milwaukee, in the county of Milwaukee and State of Wisconsin.

FRANK G. HOTKA.
